FIG. 2

FIG. 3

FIG. 1

FIG. 4

FIGURE 1 is a front perspective view of a combination spare tire and wheel carrier embodying my new design.

FIGURE 2 is a front elevation thereof.

FIGURE 3 is a side view.

FIGURE 4 is a top view.

The broken lines indicating the tire and wheel assembly, and also the front of the vehicle on which the combination spare tire and wheel carrier is mounted, are for illustrative purposes only, with the dominant features of my design residing in the portion disclosed in full lines.

I claim:

The ornamental design for a combination spare tire and wheel carrier, substantially as shown and described.
